FRANK BAYLIFF, OF BUTTE, MONTANA, AND GUSTAVE M. NELL, OF DETROIT, MICHIGAN, ASSIGNORS TO CHICAGO PNEUMATIC TOOL COMPANY, OF NEW YORK, N. Y., A CORPORATION OF NEW JERSEY

SHELL MOUNT FOR ROCK DRILLS

Application filed December 24, 1927. Serial No. 242,383.

This invention relates to supporting means for drilling machines of the percussive type. It particularly concerns supports utilizing feeding means for advancing the machine to the work, such as the so-called shell mounts for drills used in drifting operations and provided with a manually actuated feed screw.

One object of the invention is to eliminate or to reduce breakage of the supporting means. Another object is to relieve such means of at least a portion of the shocks and vibration incident to the operation of a percussive machine mounted thereon. Another object is to improve generally the construction of shell mounts in order to lengthen the life of the same and to secure better results from the use thereof. Other objects will be apparent from the detailed description which follows.

20 In order to illustrate the invention concrete embodiments thereof are shown in the accompanying drawings, in which:

Fig. 1 is a top plan view of a shell mount; Fig. 2 is a side elevational view of the 25 mount shown in Fig. 1 with a rock drill supported thereon;

Fig. 3 is a plan view similar to Fig. 1 showing a modification;

Fig. 4 is a top plan view of still another 30 form of shell mount with a rock drill supported thereon; and

Fig. 5 is a top plan view of still another form of the invention.

The invention is disclosed in connection 35 with shell mounts of the conventional type comprising a channel-shaped casting or forging *a* having under-cut or longitudinally grooved sides *b* providing slide ways for the projecting flanges or wing portions *x* of a 40 rock drill *y* (Fig. 2). The feed screw *c* is suitably supported within the channel of the mount and cooperates with a feed nut (not shown) disposed in a feed nut projection *z* on the drill. The mount has adjacent its ends, 45 supports or brackets *d* and *e* providing bearings for feed screw *c* which is arranged to be rotated by suitable means such as handle *f*. Bracket *d* is supported by shell bolts *g* extending through aligned perforated ears on shell *a*. Support *d* is maintained in spaced

relation with shell *a* by suitable means interposed between it and shell *a*. In the form of the invention shown in Figs. 1 and 2 such means comprise spacing sleeves *h* and resilient means *6*. The resilient means preferably take the form of coil springs encircling the shell rods *g* and interposed between spacers *h* and the shell *a*. With this construction feed screw *c* is held rigidly against movement to the right or rearwardly of the drill but is permitted a limited range of yielding movement by springs *6* in the opposite axial direction. Support *d* can yield in one direction but support *e* is rigid. Feed screw *c* is arranged to move with support *d* and has an elongate reduced portion at its opposite end for sliding engagement with the bearing in support *e*.

The form of the invention shown in Fig. 3 is in all respects similar to that shown in Figs. 1 and 2 with the exception that the resilient means, such as springs *7*, are disposed at the forward or left-hand ends of shell rods *g* with the result that support *d* is now yieldably in the rearward or right-hand direction, which is opposite to that provided for by the first form of the invention.

In the forms shown in Figs. 4 and 5 yielding movement of feed screw *c* relative to shell *a* is provided for in both axial directions. The shell mountings in these figures have shell rods *g'* extending the full length of the same. In the form shown in Fig. 4 resilient means in the form of coil spring *8* are disposed on shell rods *g'* between spacing sleeves *h* and shell casting or forging *a* after the manner shown in Figs. 1 and 2. In addition similar coil springs *9* are disposed upon rods *g'* at their opposite ends between support *e* and shell *a*. With this construction, it is apparent that support *d* is arranged for limited yielding movement in both axial directions, springs *8* permitting the support to move to the left while springs *9* permit its movement to the right. Feed screw *c* moves with support *d* and is arranged for sliding movement in the bearing in support *e*.

In the form of the invention shown in Fig. 5, support *e* directly engages the shell casting or forging *a* as in Figs. 1-3 inclusive.

Support *d*, on the contrary, is yieldingly movable in both directions by reason of coil springs 10 on shell rod *g'* between support *d* and the ends of the rods and by similar coil springs 11 on the rods between support *d* and shell *a*. With this construction springs 10 and 11 form both the spacing and the resilient means. Feed screw *c*, as in the previous arrangements, moves with support *d* and has sliding contact with the bearing in support *e*. If desired, one of the springs on each of the shell rods *g'*, such as 10, may be arranged to lock the rod against turning movement under the vibration of the drill. In the form shown spring 10 is provided with projections 10^a at either end which fit in complementary recesses in the heads of bolts *g'* and in support *d* respectively.

From the above it will be apparent that the present invention provides for limited yielding movement of the feed screw of a shell mounting in one or both axial directions. By this arrangement the wear upon the feed screw of the mounting and upon the feed nut of the drill is reduced. The shell mounting is at least partly relieved of the shocks and vibration incident to the operation of the drill with a consequent elimination or reduction of breakage of parts. Such constructions also tend to increase the drilling speed inasmuch as the operator can tell by compression of certain of the springs that the steel is against the work. Further, the absorption of vibration and shocks by the resilient means tend to keep the parts of the drilling machine and of the shell mounting from loosening up.

While preferred forms of the invention have been herein shown and described, it is to be understood that the invention is not limited to the specific details thereof, but covers all changes, modifications, and adaptations within the scope of the appended claims.

We claim as our invention:

1. The combination with a percussive machine of a support providing for axial movement of said machine thereon, manually actuated means for moving said machine on said support, and resilient means for absorbing shocks and vibration of said machine in both directions.

2. The combination with a percussive drill of a shell mounting therefor, means for moving said drill upon said mounting, and means providing for cushioned movement of said first-named means in one direction.

3. The combination with a percussive drill of a shell mounting therefor providing slide ways for said drill, mechanism including a feed screw for moving said drill on said mounting, and means arranged for limited yielding movement in one direction on said mounting for supporting said feed screw.

4. The combination with a percussive drill

of a shell mounting therefor providing slide ways for said drill, mechanism including a feed screw for moving said drill on said mounting, and supports adjacent opposite ends of said mounting providing bearings for said feed screw, one of said supports being arranged for yielding movement in one direction.

5. The combination with a percussive drill of a shell mounting therefor providing slide ways for said drill, mechanism including a feed screw for moving said drill on said mounting, and supports adjacent opposite ends of said mounting, one of said supports providing a loose bearing for the adjacent end of said feed screw, the other support being mounted for limited yielding movement relative to said mounting but forming a fixed bearing for said shaft.

6. A shell mounting for rock drills comprising a member having guide ways to receive wing projections on the drill, a feed screw for moving the drill upon said member, a support providing a bearing for said screw disposed in spaced relation to said member, and means permitting limited yielding movement of said support relative to said member.

7. A shell mounting for rock drills comprising a member having guide ways to receive wing projections on the drill, a feed screw for moving the drill upon said member, a support providing a bearing for said screw, means securing said support to said member but in spaced relation to the latter, and resilient means permitting limited movement of said support on said first-named means.

8. A shell mounting for rock drills comprising a member having guide ways to receive wing projections on the drill, a feed screw for moving the drill upon said member, bolts extending from said member, a support carried by said bolts and providing a bearing for said screw, and spacing and resilient means interposed between said support and said member.

9. A shell mounting for rock drills comprising a member having guide ways to receive wing projections on the drill, a feed screw for moving the drill upon said member, bolts extending from said member, a support carried by said bolts and providing a bearing for said screw, and coil springs on said bolts between said support and said member.

10. A shell mounting for rock drills comprising a member having guide ways to receive wing projections on the drill, a feed screw for moving the drill upon said member, bolts extending from said member, a support carried by said bolts and providing a bearing for said screw, and resilient means on said bolts on opposite sides of said support.

11. A shell mounting for rock drills comprising a member having guide ways to receive wing projections on the drill, a feed screw for moving the drill upon said mem-

ber, bolts extending from said member, a support carried by said bolts and providing a bearing for said screw, and coil springs on said bolts on opposite sides of said support.

5 12. A shell mounting for rock drills comprising a member having guide ways to receive wing projections on the drill, a feed screw for moving the drill upon said member, bolts extending from said member, a support carried by said bolts and providing a bearing for said screw, resilient means on said bolts on opposite sides of said support, and means utilizing certain of said resilient means for locking said bolts against turning.

10 13. A shell mounting for rock drills comprising a member having guide ways to receive wing projections on the drill, a feed screw for moving the drill upon said member, bolts extending from said member, a support carried by said bolts on opposite sides of said support, and means utilizing certain of said springs for locking said bolts against turning.
